[57] CLAIM

The ornamental design for an automotive backseat organizer, as shown and described.

DESCRIPTION

FIG. 1 is a front perspective view of the automotive backseat organizer, showing my new design and including environment, the dashed lines comprising no portion of the claimed design;

FIG. 2 is a reduced front elevation view of the automotive backseat organizer illustrated in FIG. 1;

FIG. 3 is a reduced top plan view of the automotive backseat organizer illustrated in FIG. 1;

FIG. 4 is a reduced bottom plan view of the automotive backseat organizer illustrated in FIG. 1;

FIG. 5 is a reduced left elevation view of the automotive backseat organizer illustrated in FIG. 1;

FIG. 6 is a reduced rear elevation view of the automotive backseat organizer illustrated in FIG. 1; and,

FIG. 7 is a reduced right elevation view of the automotive backseat organizer illustrated in FIG. 1.

The crisscross pattern on the lower half of the two compartments surrounding the center pocket and on the lower compartment FIGS. 1-5 and 7 is representative of mesh.

The dashed lines on the organizer in FIGS. 1, 2 and 6 are understood to represent stitching.

The broken line showing the environment in FIGS. 1-5 and 7 is for illustrative purposes only and forms no part of the claimed design.
